Term of patent 14 years

(Cl. D70—2)

FIG. 1

FIG. 2

FIG. 3

FIG. 1 is a front elevational view of a control plate for a sewing machine or the like showing my new design; FIG. 2 is a right-side elevational view thereof; and FIG. 3 is a vertical cross-sectional view of the control plate.

The essential features of my design reside in the portions shown in full lines in the drawings.

I claim:

The ornamental design for a control plate for sewing machine or the like, as shown and described.
